United States Patent Office

Des. 211,589
Patented July 2, 1968

211,589

CHILD'S PLAYGROUND RIDER OR SIMILAR ARTICLE

Ronald W. Zick, Torrance, Calif., assignor to Jamison,
Inc., Torrance, Calif., a corporation of California

Filed May 1, 1967, Ser. No. 6,916

Term of patent 14 years

(Cl. D34—5)

FIG. 1.

FIG. 2.

FIG. 3.

FIGURE 1 is a perspective view of a child's playground rider or similar article, illustrating my new design;

FIGURE 2 is a side elevational view of a child's playground rider or similar article, illustrating my new design; and

FIGURE 3 is a top plan view of a child's playground rider or similar article illustrating my new design.

I claim:

The ornamental design for a child's playground rider or similar article, as shown.
